UNITED STATES PATENT OFFICE

90,892

DESIGN FOR A RINGLETER

James Korney, New York, N. Y.

Application May 19, 1933. Serial No. 48,164

Term of patent 7 years

To all whom it may concern:

Be it known that JAMES KORNEY, a citizen of the United States, residing at New York, in the county of New York and State of New York, has invented a new, original, and ornamental Design for a Ringleter, of which the following is a specification, reference being had to the accompanying drawing, forming part thereof.

Fig. 1 is a side elevational view of a ringleter showing my new design.

Fig. 2 is a plan view of Fig. 1.

Fig. 3 is a side elevational view similar to Fig. 1 but illustrating the ringleter in an open position.

Fig. 4 is an enlarged sectional view taken on the line 4—4 of Fig. 1.

Fig. 5 is a perspective view of Fig. 1.

I claim:—

The ornamental design for a ringleter as shown and described.

In testimony whereof I affix my signature.

JAMES KORNEY.
